UNITED STATES PATENT OFFICE.

OTTO E. EDSTROM, OF SAN FRANCISCO, CALIFORNIA, ASSIGNOR, BY DIRECT AND MESNE ASSIGNMENTS, OF ONE-THIRD TO ALBERT B. OLSTON, OF BARRINGTON, ILLINOIS, AND TWO-THIRDS TO EDSTROM MACHINERY COMPANY, OF GARY STATION, ILLINOIS, A CORPORATION OF ILLINOIS.

WRAPPING-MACHINE.

1,375,369.

Specification of Letters Patent. Patented Apr. 19, 1921.

Application filed September 19, 1918. Serial No. 254,801.

To all whom it may concern:

Be it known that I, Otto E. Edstrom, a citizen of the United States, and a resident of the city of San Francisco, in the county 5 of San Francisco and State of California, have invented certain new and useful Improvements in Wrapping-Machines; and I do hereby declare that the following is a full, clear, and exact description of the same, 10 reference being had to the accompanying drawings, and to the numerals of reference marked thereon, which form a part of this specification.

My invention relates to a machine for providing a cable with a loop or eye, and has reference more particularly to a machine for wrapping a wire around the portions of the cable at each side of the loop so as to fasten same together.

20 An object of my invention is to provide a machine for wrapping a wire around the cable and turned back end thereof so as to fasten same together and form an eye or loop in the end of the cable.

25 Another object of my invention is to provide a machine for wrapping a wire around a cable and the turned back end thereof, in closely arranged coils which continue beyond the turned back end of the cable so as 30 to bind the loose end of the cable firmly in place and make a strong neat connection.

Another object of my invention is to provide a machine for winding a wire around a cable and the turned back end thereof so 35 as to securely fasten same together and form an eye or loop in the end of the cable, the wire being automatically wrapped with spaced windings to permit soldering between sections of the wrapping wire.

40 Another object of my invention is to provide a machine for winding a wire around a cable and the turned back end thereof, and having means for automatically removing a clip or tie on the end of the turned back 45 portion of the cable as the winding approximates this point.

My invention also has other objects which will appear from the following specification and the accompanying drawings.

50 On the drawings:

Figure 1 is a front view of a machine em-

bodying my invention and having portions thereof at one end broken away.

Fig. 2 is an enlarged top view of the winding mechanism of the machine. 55

Fig. 3 is a view looking at the left hand end of the machine shown in Fig. 1.

Fig. 4 is a view partly in section on the line 4—4 of Fig. 2.

Fig. 5 is an enlarged sectional view on the line 5—5 of Fig. 4. 60

Fig. 6 is an enlarged view, partly in section, of the cable holding mechanisms.

Fig. 7 is a side view of the loop holding mechanism with the jaws expanded. 65

Fig. 8 is a sectional view of the loop holding mechanism, taken on the line 8—8 of Fig. 7.

Fig. 9 is an enlarged end view of the loop holding mechanism, with a portion thereof in section on the line 9—9 of Fig. 7. 70

Fig. 10 is a sectional view on the line 10—10 of Fig. 6.

Fig. 11 is a side view of the cable holding mechanism shown in Fig. 6, with the jaws thereof open.

Fig. 12 is an inner face view of one of the jaws or levers of the cable holding mechanism.

Fig. 13 is an enlarged front view of the 80 shoe for guiding the wrapping wire on to the cable.

Fig. 14 is an enlarged sectional view on the line 14—14 of Fig. 4.

Fig. 15 is an enlarged view of the mutilated screw and tooth engaging same for advancing the cable in the operation of winding. 85

Fig. 16 is a sectional view on the line 16—16 of Fig. 15.

Fig. 17 is an enlarged sectional view on the line 17—17 of Fig. 4, showing the yieldable collar.

Fig. 18 is a detail view of the yieldable collar shown in Fig. 17. 95

Fig. 19 is a side view of the finished loop of the cable.

As shown on the drawings:

The supporting frame for this machine is shown herein of a pipe construction and 100 comprises the standards 1 and 2, with foot plates 3 for securing the machine to the

floor. At the upper end of the standards 1 and 2, are the brackets 4, 4^a and 5, respectively, each of which has an eye at each side thereof engaged by and secured to the parallel longitudinal frame members 6, and each also has an intermediate elevated bearing within which are journaled the tubular shafts hereinafter described. The brackets 4 and 4^a, between which the winding mechanism is located, are also provided with the intermediate bearings 8, with the bushings 9 and 10 therein within which is journaled the shaft 11. The brackets 4, 4^a and 5 may also be connected to the floor by means of turnbuckles 12 and rods 13, shown in Fig. 3, to hold the machine firmly in position.

Journalized in the end bracket 4 and an intermediate bracket 14, which latter is carried by the longitudinal frame members 6, is a tubular shaft 15, having an opening therethrough, through which the cable operated upon and the loop end thereof may be drawn, and the bearings of the brackets 4 and 14, which support this hollow shaft 15, are provided with bushings 16, which are held in place by the bearing caps 17, with which the bearings are provided to permit adjustment and replacement of the bearings. At the inner side of the bearing 14 the hollow shaft 15 has the chuck head 18 threaded thereon, as shown in Fig. 6, or otherwise secured on the shaft 15, and affording a shoulder engaging the bearing 14 to hold the shaft 15 from endwise movement, and there is a large gear 19, secured on the shaft 15 and engaging the opposite side of the bearing 14 to hold the shaft from endwise movement in the opposite direction. A driving pulley 20, is also mounted on the shaft 15, and is connected 40 with any convenient source of power so as to operate the shaft 15 in the direction indicated by the arrow in Fig. 4.

Mounted in alignment with the hollow shaft 15 is another hollow shaft 21, which is journaled in the upper bearings in the brackets 4, 4^a and 5, which said bearings also have the bushings 22, held in place by bearing caps 23. This hollow shaft 21 is adapted to contain the cable to be operated on, and in order to accommodate cables of various lengths, other standards 2 and brackets 5 may be provided in addition to those shown in the drawings, and the shaft 21 and frame members 6 are constructed with couplings 24 and 25, respectively, to permit increase or decrease in the length of the machine so as to enable it to be used with cables of different lengths.

The hollow shaft 21 is mounted to slide 60 lengthwise in the supporting bearings, and adjacent the inner end is supported in a pair of spaced bearing brackets 26, which are carried by the frame members 6. The bearings for the shaft 21, in these brackets 26, are provided with the bushings 27, similar

to the other bearings hereinbefore described and have the sleeve 28 mounted to rotate therein and provided with a collar 29 at each end engaging the outer face of the adjacent bearing. The shaft 21 is inserted through 70 the sleeve 28 and has a long key or spline 30 slidably engaging a keyway in the sleeve 28, so that the shaft is caused to turn with the sleeve and may slide endwise in the sleeve, and there is a gear 31 fastened on the sleeve 75 28, between the bearing brackets 26, by means of a set screw or in any other suitable manner. The gear 31 is of the same size as the gear 19, previously described, and is operated therefrom by means of the countershaft 80 33, which is journaled in the bearings 34, at the rear of the machine, and has a pinion 35 at each end of the same size meshing with the gears 19 and 31, so that when the shaft 15 is rotated the shaft 21 is likewise rotated 85 in the same direction and at the same rate of speed.

The inner ends of the shafts 15 and 21 are separated a sufficient distance to properly position the clutch members or cable holding 90 mechanisms with which the inner end of each shaft is provided for holding the loop end of the cable which is to be wrapped, the clutch on the first mentioned shaft being adapted to grip the loop end or eye of the 95 cable, and the clutch of the latter shaft being adapted to engage the cable and turned back end thereof.

The end of the cable which is to be formed with the eye or loop is cut diagonally so as 100 to provide an inclined end, and afford a neat joint in the finished product, and the cut end is temporarily inclosed in a retaining cap or clip 37, or may be wrapped with wire or otherwise held to prevent spreading or unwinding of the cable strands. A thimble 38 is placed in the looped end of the cable and the cable held around the thimble, during the wrapping operation, by the chuck with which the shaft 15 is provided. This chuck comprises an end plate 39, which is secured to the head 18 by means of the cap screws 40, and is centrally perforated at 41 to permit the cable to be drawn therethrough, and the portion of the plate, which is cut away to afford the opening 41, is bent outwardly, as at 42, to support the plate 43, on which the chuck mechanism is mounted. A stop or abutment plate 44 is detachably mounted on the inner face of the plate 43, by means of the screws 110 45, so that it may be replaced by other similar plates to adapt the machine for operation upon cables of different sizes, and the outer end of this plate 44 is bent across in front of the opening 41, and divided into upper and lower arms 46, with oppositely arranged notches 47, adapted to engage the bend in the cable and hold same so that the turned back end of the cable and the portion of the cable to which it is to be secured are concen- 120 130

trically arranged with reference to the shafts 15 and 21. A jaw 48 is pivotally mounted at each side of the plate 44 on pivot pins 49, the ends of which are connected by means of 5 the strap 50, for the purpose of bracing the jaws 48, and plate springs 51, are mounted on the plate 43 to engage the inner face of each jaw 48, and press outwardly against same. The forward ends of the jaws 48 are 10 bent inwardly as at 52, and each is notched on the end at 53, to engage the looped cable on the thimble 38 at points where the cable at each side of the loop 38 converges, so that when the jaws 48 are pressed together so as 15 to engage the cable on the thimble, the thimble and cable thereon are forced into engagement with the notches 47 in the arms 46 of the abutment plate 44, and the cable thereby drawn tight around the thimble 38 20 and the cable and thimble thus securely clamped in the chuck.

For clamping the arms or jaws 48 together there is a bar 54 at one side of the position occupied by the looped cable in 25 the chuck, and extending through openings adjacent the free ends of the jaws, as shown, the said bar 54 and openings therefor in the arms 48 being preferably rectangular or otherwise shaped so as to hold the bar from 30 turning and permit movement of the said bar in the direction of its length through the said opening. A cam 55, having an operating handle 56, is pivoted at one end of the bar 54, and there is a collar 57 adjust- 35 ably secured at the other end of the bar 54, both being arranged to engage the outer faces of the jaws 48, so that when the lever 56 is turned inwardly from the position shown in Fig. 7, to the position shown in 40 Fig. 6, rotation of the cam 55 draws the free ends of the arms 48 together so as to clamp the cable and thimble in the chuck. For providing adjustment of the collar 57 to enable the jaws 48 to hold cables and thim- 45 bles of various sizes, one side of the bar 54 is toothed as at 58, and the collar 57 provided with an inwardly projecting lip 59, which may be engaged with the various teeth 58 of the bar 54, and held in such en- 50 gagement by means of the set screw 60, which is threaded through the opposite side of the collar 57, against the back of the bar 54. The upper end of the collar 57 is offset at 61 to provide a wide engaging face to 55 bear against the outer face of its jaw 48.

On the shaft 15, adjacent the outer end, is a hand wheel 79 to permit manual operation of the mechanism to permit convenient access to the parts. On the inner end of the 60 other shaft 21, a ring 61 is secured and provided with diametrically opposite bearings 62, in which are pivotally mounted a pair of levers or arms 63, which reach forwardly beyond the end of the shaft 21, and are pro- 65 vided at the forward ends with internally

grooved grippers 64, each of which is adapted to straddle one of the portions of the cable to be wrapped and to hold same tight together and side by side so that they will be bound firmly. On the inner face of each 70 of the levers 63 is a plate 65, having an in-turned finger 130, which, when the levers 63 are pressed together to grip the cable, overlap and are separated substantially the width of the cable so as to hold the two portions of the cable to be bound together, side by side, as shown in Fig. 10, and these fingers 130 serve as strippers to automatically remove the end clip 37, or other fastening which may be used to temporarily prevent 80 unwinding of the end strand of the cable, as the winding approaches that portion of the cable.

The levers 63 are pivoted intermediate of their ends as shown, and the ends thereof 85 opposite the grippers 64 project back over the hollow shaft 21, so as to be engaged by the flange 131, of a collar 66, which slides lengthwise of the shaft 21. This collar 66 slides on a sleeve 67, which is secured to the 90 shaft by a set screw 68, or in other convenient manner, and has a hand wheel 69 at the end thereof which may be used for turning the shaft 21 to facilitate access to the work, and a spring 70 is interposed between the 95 hand wheel 69 and the collar 66, so as to normally force the collar and flange 131 thereof to engage the rear end of the levers 63 and force the forward ends thereof inwardly to securely grip the cable. When 100 the cable is to be inserted in place for wrapping, the collar 66 is retracted beyond the ends of the levers 63 and said levers tilted to the position shown in Fig. 11 and held in such position by the pressure of the collar 105 flange 131.

In wrapping the cable, the looped end thereof is held in the chuck on the inner end of the shaft 15, and the shaft 21 and gripping levers 63 thereon are gradually moved 110 away therefrom at a rate corresponding with the advance of the wrapping wire on the cable. For this purpose the shaft 11 is provided with a worm or screw 71, and the shaft and worm are driven by means of the 115 gears 72, 73 and 74 from the shaft 15 at the proper speed to retract the shaft 21 in the required manner. The rate of movement required of the shaft 21 depends on the size of the wire used in wrapping the cable, and 120 as this wire varies in wrapping cables of different sizes, the gears 73 and 74 are detachable by removing the cap screws 75 and 76, respectively, and the intermediate gear 73 is mounted on a swinging bracket 125 77, which is adjustable circularly on the sleeve extension 78 of the bearing 10, so as to permit the use of different sized gears to secure the proper rate of speed for the shaft 11 and worm 71.

Slidably mounted on the shaft 11, and inclosing the worm 71, is a tube 80, which has a bushing 81 at each end engaging the shaft 11 and permitting the shaft to turn independently of the tube 80, and there is also an external bearing 132 for the tube 80 on the bracket 14. This tube 80 is connected with the shaft 21 by a bracket composed of the half sections 82, which are centrally spaced apart to provide a space for mechanism to be hereinafter described. The corresponding ends of these half sections at each side of the open space therebetween are provided with the half clamps 84 and half bearings 85, the former of which are secured to the end of the tube 80 by means of the bolts 86, and the latter of which are held to loosely embrace the shaft 21 by means of the bolts 87. Longitudinal movement of the bearing 85—85 on the shaft 21 is restricted by the collar 88 at one side, which is secured on the shaft 21, and by means of the resilient collar 89 at the other side, which is likewise secured on the shaft 21.

The bracket connection 82 normally controls the longitudinal movement of the shaft 21, and is geared to retract the shaft 21 as nearly as possible in accordance with the winding of the wire on the cable. However, the gage of the winding wire sometimes varies and necessitates a slight movement of the shaft 21 in advance of the movement normally imparted thereto by the gearing, and the resilient collar 89 is provided to permit such advance movement to the shaft 21. This collar, as is shown in Figs. 17 and 18, has an annular flange 90 at one end and a ring 91 embraced by the flange 90 and fitting loosely on the shaft 21. A plurality of plate springs 92 are secured to the ring 91 and extend up from the surface thereof so that the free ends thereof engage against the collar 89 inside the flange 90, and as the ring 91 abuts against the bearing 85—85 of the bracket 82—82, and as the collar 89, is secured to the shaft 21, by means of the set screw 93, a limited endwise movement of the shaft 21, is permitted against the tension of the springs 92.

A collar 94, is secured on the tube 80, at a distance from the bracket 82—82, and has the lever 95, pivoted thereto so that the end thereof extends between the half sections 82, of the bracket, and a tooth 96 is mounted on the lever 95, and extends through a slot 97 in the tube 80, and has the inner end formed as at 98 to engage the worm or screw 71. A lever 99, is pivoted between the half sections of the bracket 82, and has the handle 100, normally projecting from therebetween, and said lever is connected with the outer end of the lever 95, so that when the handle 100, is pressed inwardly, the lever 95, is swung on its pivot and the

tooth 96, lifted from engagement with the thread of the worm 71. A spring 101, mounted between the half sections of the bracket 82, engages the lever 95 to normally hold same downward so that the tooth 70 96, is in operative engagement with the worm 71.

In wrapping cables it is desirable to provide gaps or spaces separating closely wound portions and this is effected with my device 75 in the following manner. A spring 103, of sufficient strength to move the shaft 21, and the parts connected therewith, has one end attached to the frame of the machine, as at 104, and the other end to the bracket 80 82—82, by connection with one of the bolts 86, or in any other suitable manner, so that the engagement of the tooth 96, with the worm 71, holds the shaft 21, and bracket 82—82, and parts connected therewith from movement under the tension of the spring 85 103. The worm 71, may be mutilated as at 105, and 106, by having portions of the thread cut away at these points, or if desired, the worm may be cut with the thread offset at the point required so that when the mutilated or offset portion of the thread is reached by the tooth 96, the bracket 82—82 and shaft 21, and parts connected therewith are permitted to jump a short distance 95 under the tension of the spring 103, so as to afford the gaps or spaces 102 and 107, in the winding of the wire on the cable corresponding to the mutilated portions 105 and 106, respectively, of the worm.

For feeding the wire to be wrapped around the cable, there is an arm 108, mounted on the tube 80, and extending to a point adjacent the inner ends of the grippers 64, which latter move along the portion of the cable to be wrapped, and this arm 108 has an adjustable shoe or guide 109 secured to the end thereof by means of the threaded stem 110 and locked in position by means of the lock nut 111. This shoe is tapered so that it may be adjusted in close proximity to the end of the grippers 64, and has a groove 112, in the front face thereof to guide the wire on to the cable directly in front of the grippers 64. 110 The arm 108 for guiding the wire on to the cable moves with the tube 80, so that its movement corresponds to that of the shaft 21 and the grippers 64 adjacent which the wire is to be wound, and said arm may have an adjustable connection 113, for changing the position of the shoe 109, if required.

Also supported on the tube 80, so as to move therewith is the frame for supporting the wrapping wire comprising the arms 114, which are clamped on to the tube 80, and have the bearings 115 at the outer ends thereof to support the shaft 116, on which the spool 117, of wrapping wire 118 is 130

loosely mounted. The bearings 115 have the upper half sections thereof pivotally connected with the lower half sections and detachably held to engage the shaft 116 by 5 clamp nuts 118, which may be readily opened to permit removal and replacement of the spool of wire. A round bar 119 is mounted between the arms 114, above the spool of wire so that the wire 118 may be 10 looped thereabout one or more times to afford sufficient tension to wind the wire tight around the cable, and a spring 120, is interposed on the shaft 116 between one end of the spool 117 and one of the bearings 115, and serves to afford a frictional resistance to the operation of the spool 117 to afford tension to the wire 118. The connection of the arms 114 of the wrapping wire support with the tube 80 is sufficiently tight 15 to insure movement of the wrapping wire supporting frame with the tube, and at the same time permit the frame 114 to be swung upwardly around the tube 80 to provide sufficient wire for making the connection with 20 the cable in starting the wrapping operation.

The operation is as follows:

The machine is first set up for the size of cable and wrapping wire which is to be 30 used, by providing a plate 44 of suitable size for the end of the loop to be formed, and by adjusting the collar 57 to properly clamp the loop in the chuck. The stripper fingers 130, are also adjusted laterally to accommodate the width of the cable to be wrapped. The gears 73 and 74, are changed if required, to drive the worm 71, at the speed required to move the wrapping mechanism as the cable is wrapped, the rate of 40 speed being determined by the gage of the wrapping wire employed. The cable is previously cut in a diagonal direction and provided with a retaining cap or clip 37, or other means for retaining the ends of the 45 cable from spreading or unwinding and the end of the cable is bent back at the point where the loop is to be made and so that the beveled face at the end of the cable faces outwardly. The jaws 48 of the loop chuck 50 are opened, as shown in Fig. 7, and the levers 63, are opened up as shown in Fig. 11. The looped end of the cable is then inserted through the pipe 21, and the thimble 38, fitted into the looped end of the cable, and 55 the thimble and cable thereon is then clamped between the jaws 48, and the abutment plate 44, by swinging the hand lever 56 rearwardly to the position shown in Fig. 6.

60 The wrapping wire carrier 114 is then raised slightly to advance the wrapping wire 118 sufficiently so that the end may be caught in any convenient manner at the inner end of the thimble 38, so that when 65 the cable is rotated the wire 118 will be

wrapped therearound, and the wire is laid in the groove 112 of the wire guide 109, and the wrapping wire frame 114 permitted to swing down to the normal position. The levers 63, are then tilted forwardly so that 70 the stripping plates 65 are on opposite sides of the two portions of the cable to be wrapped, and the grippers 64 engage the two portions of the cable to be wrapped immediately adjacent the inner end of the 75 thimble 38, care being taken that the wrapping wire 118 is beyond the ends of the grippers 64, so that it will be wound on the cable. The forward tilting of the levers 63 releases the rear ends of said levers from 80 engagement with the front face of the flange 131, of the ring 66, and the tension of the spring 70 forces the ring under the rear ends of the levers and automatically clamps the forward end thereof in engagement with 85 the cable.

The machine is then thrown into operation by applying power to the pulley 20, to rotate the shafts 15 and 21 in the direction indicated by the arrows in Fig. 4, and the 90 cable and portions thereof to be wrapped are caused to turn with these shafts. As the shafts and cable rotate the wrapping wire 118 is wound on the two portions of the cable which are to be bound together, 95 being guided thereon by the shoe 109, and also by the ends of the gripper 64, so that the wrapping wire is wound in a close tight coil. As the wire is wound on the cable the point of application continually advances at a rate depending upon the gage of the wrapping wire employed, and as the gears 73 and 74 operate the worm 71 so as to permit advance of the shaft 21 and hollow tube 80 at the same rate of speed, 100 the wrapping wire will be fed on to the cable so as to provide a close tight coil except at the places where the gaps are to be provided for soldering.

When the worm 71 has turned sufficiently 110 so that the tooth 96 reaches the point where the thread of the worm is broken away, the spring 103 causes the shaft 21, tube 80 and parts connected therewith to jump a distance until the tooth 96 reengages the 115 thread, thus affording a gap or unwound place between closely wound coils of the winding wire, for soldering to insure a tight hold of the winding wire on the portions of the cable wrapped thereby. The points 120 at which the open places in the winding are to be provided depend upon the location of the places in the worm where the thread is mutilated or offset, and the worm may be constructed to provide any number of unwound places and spaced in any desired manner.

When the cable is wrapped as far as required, the machine is stopped and the 125 clutches released, and the wrapping wire 118, 130

cut off at the end of the wrap, whereupon the loop just made may be moved to one side to pass the arms 46 of the plate 44, and inserted through the opening 41 in the plate 39, and drawn out through the hollow pipe 15, the cable at such time passing freely between the arms 46 of the plate 44.

To reset the machine, the lever 100 on the bracket 82 is pressed inwardly, thereby lifting the lever 95 and the tooth 96 from engagement with the worm, and the shaft 21 and tube 80 and parts connected therewith may be moved back to the starting position.

While I have shown and described my invention in a preferred form, I am aware that various changes and modifications may be made therein without departing from the principles of my invention, and I therefore do not purpose limiting the patent granted hereon otherwise than necessitated by the prior art.

I claim as my invention:—

1. In a machine of the class described the combination with a rotatable chuck of cam controlled means thereon for removably holding the article to be wrapped, and means for winding a wire around said article in spaced sections, each section comprising a plurality of closely arranged coils of said wire.

2. In a machine of the class described the combination of adjustable spring controlled means for holding the looped portion of a cable, a notched plate for receiving said looped portion and means for winding a wire around the portions of the cable intermediate of which the loop is formed, so as to bind said portions together.

3. In a machine of the class described the combination of clamping members, cam means for moving the same into position for holding the looped portion of a cable, pivoted means adapted to slide along the portions of the cable intermediate of which the loop is formed, for the purpose of holding the cable portions to be wrapped side by side, and means for wrapping a wire around said portions of the cable intermediate of said sliding means and the looped portion of the cable.

4. In a machine of the class described the combination with a rotatable chuck of pivoted clamping members thereon, springs for moving the same apart, means for moving said clamping members toward one another into position for holding a plurality of cable portions side by side, and means for wrapping a wire around said cable portions to bind them together.

5. In a machine of the class described the combination of spaced spring controlled cam actuated members for holding a plurality of cable portions side by side, a rotatable support therefor, and means for winding a wire around said cable portions.

6. In a machine of the class described the combination of spaced rotatable means for holding a plurality of cable portions side by side, means for winding a wire around said cable portions intermediate of said spaced holding means to bind said cable portions together, and means for withdrawing one of said rotatable holding means along said cable portions in advance of the winding of the wire on the cable portions.

7. In a machine of the class described the combination of slidable and rotatable means for holding a plurality of cable portions side by side, means for winding a wire in successive coils around said portions to bind them together, and a wire guide adapted to feed the wire onto the cable portions in a continually advancing position so as to be wound in successive coils thereon.

8. In a machine of the class described the combination of pivoted clamping members, spring actuated means for holding said members in clamping position for holding a plurality of cable portions side by side, means for guiding a wrapping wire so as to be wound around the said cable portions to bind them together, and means for simultaneously advancing said holding means and guiding means along the said cable portions.

9. In a machine of the class described the combination with a rotatable chuck, of spring controlled clamping members pivoted thereon, cam means for moving the same into position for holding an article to be wrapped, means for winding a wire around said article, and a wire guide automatically movable lengthwise of said article to continually advance the point of feeding the wire onto the article.

10. In a machine of the class described the combination of rotatable means, spring controlled jaws pivotally mounted thereon, cam means for moving said jaws into clamping position for holding a cable to be wrapped, a guide for feeding a wire onto said cable so as to be wound thereon by the rotation of the holding means and cable, and means for advancing the said guide along the cable immediately in advance of the point where the wire is winding on said cable.

11. In a machine of the class described the combination of adjustable cam controlled means for removably holding a plurality of cable portions side by side, means for winding a wire around said portions to bind them together, and a mutilated worm for effecting an irregular winding of said wire to provide spaces intermediate of adjacent series of closely arranged coils.

12. In a machine of the class described the combination with pivoted members, of a bolt projecting therethrough, a cam on said bolt adapted to be actuated to move said pivoted members into position to hold

looped cables of different sizes, and means for winding a wire around the portions of the cable between which the loop is formed so as to bind said portions together.

45

5 13. In a machine of the class described the combination of a hollow rotary shaft, spring controlled cable grips pivotally mounted on one end thereof adapted to hold a pair of cable portions side by side, a chuck 10 adjacent the said end of the shaft and rotatable therewith and adapted to hold a loop of the cable formed intermediate of said cable portions, means for feeding a wire so as to be wound onto the said portions, and 15 means for moving the cable grip and wire feeding means along the cable portions as the wire is wound thereon.

14. In a machine of the class described the combination of means for holding two 20 cable portions side by side, a wire guide for feeding a wire so as to be wound around said cable portions, and mechanism for providing relative movement lengthwise of the cable portions between the said cable portions and wire guide to continually advance the point of winding on the said portions, 25 said mechanism being provided with spring controlled jump acting means operable at intervals to provide spaces between sections 30 of the winding on the said portions.

15. In a machine of the class described the combination of means for holding a pair of cable portions side by side, a wire guide for feeding a wire so as to be wound on the 35 cable portions, spring controlled means exerting a tension to move the said guide lengthwise of the cable portions, and a worm regulating such lengthwise movement to provide a close winding of the wire on the 40 cable portions, said worm being provided with mutilated portions permitting the said tensioning means to suddenly advance the

wire guide and provide a gap in the otherwise uniform winding of the wire on the cable portions.

50

16. In a machine of the class described the combination with a rotatable chuck, a notched plate thereon for receiving the looped portion of a cable, apertured clamping jaws pivotally mounted on said chuck, 55 springs acting to hold said clamping jaws separated, a bolt projecting through said jaws, and a cam on said bolt adapted to be operated to move said jaws toward one another to clamp against the looped portion of 55 the cable.

17. In a machine of the class described the combination of means for holding the looped portion of a cable, cable gripping means for holding the portions of the cable 60 intermediate of which the loop is formed, side by side, stripping means on said gripping means slideable along the said cable portions, means for winding a wire on said cable portions intermediate of the aforesaid 65 loop holding means and cable gripping means, and means for gradually withdrawing the cable gripping means and stripping means as the wire is wound on the said cable portions.

70

18. In a wrapping machine the combination with a means for wrapping a wire around an article, of a mutilated worm controlling the operation of said means to cause the wire to be wound in connected 75 separated coils on the article.

In testimony whereof I have hereunto subscribed my name in the presence of two subscribing witnesses.

OTTO E. EDSTROM.
